US00D579245S

(12) **United States Design Patent**
Daino et al.

(10) **Patent No.:** **US D579,245 S**
(45) **Date of Patent:** **** Oct. 28, 2008**

(54) **DRAWER**

(75) Inventors: **Franco Fabio Daino**, Muskego, WI
(US); **Richard J. Kolaczewski**, Gurnee,
IL (US)

(73) Assignee: **Waterloo Industries, Inc.**, Waterloo, IA
(US)

(**) Term: **14 Years**

(21) Appl. No.: **29/295,476**

(22) Filed: **Sep. 28, 2007**

(51) **LOC (8) Cl.** **06-06**

(52) **U.S. Cl.** **D6/510**

(58) **Field of Classification Search** D3/319;
D6/336, 432, 436, 441, 445–446, 448, 509–511;
D8/300; D34/27; D32/25; 312/108, 109,
312/199, 204, 257.1, 297, 330.1, 348.4

See application file for complete search history.
